UNITED STATES PATENT OFFICE.

ELLIICK H. GOLLINGS, OF CHICAGO, ILLINOIS, ASSIGNOR TO THE GOLLINGS BI-CENTRIC PUMP COMPANY, OF SAME PLACE.

ROTARY PUMP.

SPECIFICATION forming part of Letters Patent No. 448,609, dated March 17, 1891.

Application filed December 14, 1889. Renewed January 8, 1891. Serial No. 377,173. (No model.)

To all whom it may concern:

Be it known that I, ELLICK H. GOLLINGS, of Chicago, in the county of Cook and State of Illinois, have invented certain new and useful Improvements in Bicentric Rotary Pumps; and I do hereby declare that the following is a full, clear, and exact description thereof, reference being had to the accompanying drawings, and to the letters of reference marked ⁵ thereon, which form a part of this specification.

This invention relates to that class of rotary pumps (illustrated in the several prior applications for Letters Patent of the United States, Serial Nos. 301,675 and 315,250, filed by me March 1, 1889, and June 22, 1889, respectively) in which a concentrically-rotating shell contains and rotates an eccentrically-mounted wheel having radial wings or an equivalent chambered construction, and in which water or other liquid to be pumped is supplied to and discharged from the interior of the shell through an axial support for the rotating parts. In said several applications for patent ¹⁵ it is set forth that the interior of the shell is divided (substantially in the plane of greatest eccentricity) into two compartments by the aid of certain movable parts, which operate as prolongations of the radial wings or ²⁰ division-walls of the chambered eccentric wheel, and that by the rotation of the shell and wheel the fluid to be pumped is admitted to one of these compartments and expelled from the other.

The present invention has for its object to provide a construction of the machine with respect to the movable prolongations of the wings on the eccentric wheel with a view to the division of the shell interior into two compartments.

The accompanying drawings illustrate the special improvement above referred to in connection with another improvement, which consists in the provision of the inlet and outlet ⁴⁵ of one end of the machine, and which is set forth in another application for Letters Patent, Serial No. 333,766, filed by me simultaneously herewith.

Figure 1 is a vertical central section of the machine in the indirect line 1 1 of Fig. 2. Fig. 2 is a transverse section in the line 2 2 of Fig.

1. Fig. 3 is a vertical section in the line 3 3 of Fig. 1. Fig. 4 is a detail in section of a modification.

A is the frame-base having two cross-pieces ⁵⁵ A', said frame-base having at one end an arched upright supporting an annular part A² and at its opposite ends an arched upright A³ supporting a socket-piece A⁴.

B B' is a non-rotating shaft having concentric portions B B and an intermediate eccentric portion B'. One end of the shaft B B' is upheld and clamped in the socket-piece A⁴, while the opposite end is sustained in a socket ⁶⁰ c, formed in a prolongation c' of the tubular casting C, which latter is in turn sustained by having a flange c² thereon bolted against the side of the frame-ring A².

D is a rotating shell composed of the end plate d, the end plate D', and the rim D², the latter being secured by bolts between the margins of the end plates d and D'. The shell D rotates on the axis of the concentric portions of the shaft B B'. As illustrated in these particular drawings, the end plate d has ⁷⁰ a packed bearing at d', and also a roller-bearing at r upon the adjacent concentric portion D of the shaft B B'. The head D' has also a roller-bearing on the adjacent concentric part of the shaft at r', and it has a packed ⁷⁵ bearing at d² upon a cylindric part c³ of the tubular casting C.

G is a symmetrical wheel mounted on the eccentric portion B' of the non-rotating shaft B B', said eccentric wheel being provided in ⁸⁵ the present instance with a roller-bearing r². The wheel G is provided with a series of peripheral recesses g, separated by wings g' of such length as to extend into contact or proximately into contact with the inner peripheral ⁹⁰ surface of the shell-rim D² on the side thereof toward which the eccentric B' projects. At all other points, therefore, said wings will be at a distance or at a greater distance from said inner peripheral surface of the shell. To ⁹⁵ provide for the prolongation of the wings g', so that passage for fluid may be cut off between the shell at the point most remote from the eccentric wheel and the adjacent wing of the latter, I employ a series of movable parts ¹⁰⁰ F, which are here shown and are desirably made in the form of cylinders or rollers.

Said rollers F fill the lateral space between the parallel marginal portions of the opposite end plates d D' of the shell, and have gudgeons f at their ends, which project into slots 5 f', formed in the parallel faces of the said end plates at a distance from the inner periphery of the rim D² suitable to allow the cylindric surfaces of the rollers to bear against such periphery. The slots f' are of 10 such length that in the simultaneous rotation of the shell and the eccentric wheel by pressure of the ends of two opposite slots against the gudgeons on one of the rollers and pressure of the roller thus supported against 15 the adjacent wing g', as shown at the bottom of Fig. 2, the other rollers may adjust themselves to a position between the wings on both sides of them severally without binding or 20 undue pressure against the extremities of the slots.

When the parts F are cylindric, they are desirably of a diameter equal to or greater than twice the length of space between the shell and the end of the wing g' most remote from 25 the shell; but if said movable parts be made in other than cylindric form—as, for example, rectangular—it is only necessary that they be of sufficient width radially of the shell to cover and close said space.

30 In Fig. 4 the rim D² of the shell is shown as having transverse depressions d⁵, the parts of which will be occupied by the rollers when their gudgeons f are in contact with the rear ends of the slots f'. This is the position of 35 the roller when concerned in imparting motion to the eccentric wheel from the shell, and substantially the position of the roller when in contact with the wing of the eccentric wheel most remote from the shell. In the 40 construction described centrifugal action upon the rollers will therefore tend to bring them into these working positions after being moved out of such positions by contact with the wings during other portions of their 45 revolution.

With the shell and eccentric wheel hereinbefore described only one chambered head or 50 end plate D' is here shown, and in combination therewith a single tubular axial support C, having both inlet and outlet passages c¹ c⁵; but, if desired, the pump may have a chambered head D' at each end, and in connection therewith a hollow axial support may be employed at each end of the machine, so as to 55 receive at one end and discharge at the other, as shown in both my said prior applications for patent.

Briefly describing the construction of the chambered head D' and the tubular support 60 C, as the same have already been fully described and claimed in the application for patent filed simultaneously herewith, I point out that said head or end plate D' is provided with a series of passages p, separated by radial webs d³, corresponding in number with 65 the number of wings g' of the eccentric wheel,

and that opposite webs d³ coincide with opposite wings g' in the plane of greatest eccentricity, so that the division of the shell extends to the interior of the chambered head 70 D' also. The projection c' has its end also in the same plane as seen in Fig. 3, and of such length as to reach into contact or close proximity with said opposite webs d³. In the construction illustrated this stationary or 75 non-rotating projection c' is a continuation of a partition C', formed in the tubular support C, for the purpose of affording inlet and outlet to and from the shell at one and the same end of the machine. 80

In the arrangement here shown the plane of greatest eccentricity is horizontal and the direction of motion is that indicated by the arrow in Fig. 2. The upper half of the machine is therefore the expulsion side and the 85 lower half the induction side thereof, and c' is the supply-passage and c⁵ the discharge-passage of the divided tube C.

I claim as my invention—

1. In a rotary pump of the general character described, the combination, with a rotating shell having suitable inlet and discharge passages, and with an interior eccentrically-supported rotating wheel provided with a series of peripheral wings, of a series of movable 95 parts supported in contact with the periphery of the shell and engaged with said shell, while having a limited movement in a direction substantially parallel with the periphery of the shell and adapted to bear against the wings 100 of the eccentric wheel.

2. In a rotary pump of the general character described, the combination, with the rotating shell having suitable inlet and outlet passages and with an interior eccentrically-supported rotating wheel provided with a series of peripheral wings, of a series of rollers supported in contact with the periphery of the shell and engaged with the shell, said rollers having a limited movement substantially at 105 right angles to the wings of the eccentric wheel and being adapted to bear against said wings, substantially as and for the purpose set forth.

3. In a rotary pump, the combination, with 115 the shell, the end plates of which have slots f', and with an eccentric wheel provided with wings g', of the series of rollers F, provided with gudgeons occupying the slots f', substantially as and for the purpose set forth.

4. The rim D² of the shell, provided with transverse depressions d⁵, in combination with the eccentric wheel having wings g' and the rollers F, substantially as described.

In testimony that I claim the foregoing as 125 my invention I affix my signature in presence of two witnesses.

ELLIOTT H. GOLLINGS.
